United States Patent Office

Des. 188,137
Patented June 7, 1960

188,137

JAR

Russell E. Thompson, Jr., Mount Prospect, Ill., assignor to Continental Can Company, Inc., New York, N.Y., a corporation of New York

Filed Mar. 13, 1959, Ser. No. 54,974

Term of patent 14 years

(Cl. D58—25)

Fig. 1.

Fig. 2.

Fig. 3.

The side of the jar opposite the side shown in Figure 1 is identical to the side shown in said figure.

I claim:

The ornamental design for a jar, as shown and described.
